UNITED STATES PATENT OFFICE.

GEORGE MARCROFT, OF PROVIDENCE, RHODE ISLAND, ASSIGNOR TO UNIVERSAL WINDING COMPANY, OF BOSTON, MASSACHUSETTS, A CORPORATION OF MASSACHUSETTS.

CONE-WINDING MACHINE.

1,348,291.

Specification of Letters Patent.

Patented Aug. 3, 1920.

Application filed October 23, 1918. Serial No. 259,344.

To all whom it may concern:

Be it known that I, GEORGE MARCROFT, a citizen of the United States, residing at Providence, in the county of Providence, 5 State of Rhode Island, have invented certain new and useful Improvements in Cone-Winding Machines, of which the following is a specification.

My invention relates to winding machines 10 and consists of an improved cone-winder for producing conical packages of thread, yarn or other textiles. The object of my improvement is to provide a machine for winding a cone-package of improved form, 15 having a convex base and a concaved apex end, whereby the yarn or other material is so disposed about its central core or support as to secure a more stable structure in the cone and a freer delivery of the yarn 20 in unwinding it therefrom. To this end my improvement consists essentially in providing means for positively and progressively shifting the traverse of the thread-guide, which deposits the coils of winding in place, 25 longitudinally of the cone-holder so that successive layers of the winding are gradually stepped forward toward the apex end of the cone to cause the base to assume a convex shape while the small end of the 30 cone becomes correspondingly concaved.

The manner and means for carrying out the improvement are fully described in the following specification, illustrated by the accompanying drawings, in which like reference characters designate like parts. In 35 the drawings:

Figure 1 is a front elevation of a well known type of winding machine showing my improvement applied thereto;

Fig. 2, an enlarged, plan view of a portion of the traverse-mechanism of the machine showing the connection between the traverse-cam and the slide which transmits motion to the thread-guide; and

Fig. 3, an enlarged, end elevation of a portion of the traverse-cam showing its connection with the traverse-slide and also illustrating different positions of the traverse-frame which carries the thread-guide as the latter recedes from the axis of the winding-spindle.

Referring first to Fig. 1, 2 designates the main frame of the winding machine in which are rotatably mounted the horizontal

winding-spindle 3 and cam-shaft 4. On the 55 rearward end of the spindle 3 is a driving-pulley 5 adapted to be rotatively connected therewith by suitable clutch-devices, not herein shown or described in detail, and through which the machine is operated from 60 a driving-belt driven from any suitable source of power. Outwardly beyond the driving-pulley 5 is a belt-pulley 6 fixedly secured to the spindle 3 and connected by a belt 7 to a lower pulley 8. The pulley 8 65 is fixed on the end of a countershaft 9 which carries a pinion 10 at its opposite end, the latter meshing with a gear 11 on the end of the cam-shaft 4. The shaft 9 is journaled in a bearing in a casing 12 which serves as 70 a gear-box and oil-reservoir for the gears 10 and 11.

On the forward end of the spindle 3 is a conical mandrel or arbor 13 which serves as a support for the paper or fiber cone-tube 75 X on which the package is wound. The thread-guide 14 which is adapted to be reciprocated opposite the cone-holder 13 is carried in a traverse-frame 15 which is formed with two arms or legs 16, 17, pivoted on the cam-shaft 4. The thread-guide 14 bears against a traverse-frame back 18 which is shaped to adapt the guide to move in a path at an angle to the axis of the cone-holder whereby it may follow the tapered 85 surface of the cone-tube X. The traverse-frame 15 swings on its bearings about the axis of the cam-shaft 4 to allow the thread-guide 14 to recede from the axis of the cone-holder 13 as the package is built up on the 90 tube X. This movement of the traverse-frame 15 outwardly away from the axis of the winding-spindle is resisted by a counter-weight 19 depending from the arm 16 of the traverse-frame 15. 95

The thread-guide 14 consists of a sheet-metal arm or plate having a forwardly-bent upper end, see Fig. 3, in which is formed a guiding-slot 20. The lower end of the guide 14 is connected to a traverse-rod 21 which slides in a slot 22 in the outer, overhanging portion of the traverse-frame 15. The rearward end of the traverse-rod 21 is connected to a slide or crosshead 23 which slides in a vertical slot 24 formed in 100 the horizontal portion of the traverse-frame 15 which extends between the two legs 16 and 17. The crosshead 23 is of substan-

tially L-shape in cross-section, as shown in Fig. 3, having a lower extension or foot 25 which abuts the under side of the frame 15 to prevent it from riding up out of its slot 24. The above described construction is common to a well known type of machine now in general use, and heretofore it has been the practice to connect the traverse-bar or rod 21 to be reciprocated from a cylindrical cam 26 mounted fast on the cam-shaft 4. As shown in Figs. 1 and 3, the cam 26 is constructed with a cylindrical rim supported by radial arms 27 extending from a central hub 28. On its periphery is a helical groove 29 which is adapted to engage a suitable roll or stud connected to reciprocate the traverse-bar 21. In my present type of construction, instead of connecting the traverse-slide 23 directly with the cam 26, I provide an intermediary means therebetween whereby during the reciprocation of the traverse-bar its traverse will be shifted to advance the thread-guide progressively outward toward the apex end of the cone. This novel and improved arrangement provides for shifting the traverse of the guide longitudinally of the cone-holder whereby to gradually displace the layers of winding which results in the concavo-convex formation at the ends of the cone being built.

Referring particularly to Figs. 2 and 3, in my present improvement the traverse-cam 26 imparts motion to an auxiliary slide or crosshead 30 which, in turn, transmits motion to the main slide 23 which is connected to the thread-guide 14 through the traverse-bar 21. The crosshead 30 is preferably constructed of sheet-metal and comprises a flat plate-portion 31 formed with two upturned ears 32, 32. The ears 32 are apertured to receive a sleeve or bushing 33 which is adapted to slide on a track or rod 34. The rod 34 extends horizontally across the top of the cam 26 with its ends supported in the uprights of the main-frame 2 of the machine, see Fig. 1. Forward of the rod or track 34 the plate 31 carries a stud 35 held in place by a nut 36 which binds its flange 37 against the under side of the plate. Rotatably mounted on the lower end of the stud 35 is a roller or bowl 40 which engages the groove 29 in the cam 26. Through this means the slide or crosshead 30 is connected to be reciprocated from the cam to slide it along its track or rod 34. Extending upwardly from the plate 31 is an arm 41 which is continued in an arcuate strip 42 formed concentric with the axis of the cam 26 as shown in Fig. 3.

Referring now to Fig. 2, the extension 42 is inclined at a sharp angle to the axis of the rod 34 on which the crosshead 30 slides. The extension 42 projects across the top of the traverse-slide 23 and is engaged by two inclined ears 43, 43 which project upwardly

from the traverse-slide, and overhang the top of the arm 42 to prevent it from being lifted out of place. These ears allow the traverse-slide 23 to move outwardly along the arm 42 while maintaining it constantly connected with the crosshead 30 whereby the two parts will move together. Referring to Fig. 3, the full lines represent the traverse-frame 15 in the position it assumes at the start of the winding when the thread-guide 14 is bearing on the surface of the cone-tube X supported on the cone-holder 13. As the winding builds up on the tube X and the package increases in diameter the thread-guide 14 will be forced away from the axis of the winding-spindle 3 and the traverse-frame 15 will be carried outwardly toward the position shown by the dash-lines in Fig. 3. As the traverse-frame 15 moves outwardly in this manner the traverse-slide 23 slides outwardly along the inclined extension or arm 42 on the crosshead 30 which acts as a cam to shift the traverse-bar 21 to displace the thread-guide 14 gradually outward in the direction of the apex of the cone.

The method of operation of the complete apparatus is as follows: In preparing the machine for operation the cone-tube or paper-shell X is slipped on over the outside of the cone-holder 13 and secured in place through any suitable means as usually provided. The thread or yarn y is then led up from its source of supply through the slot 20 in the thread-guide 14 and its end fastened to the tube X. The operator now swings the traverse-frame 15 into starting position with the guide 14 bearing against the surface of the tube X, and the machine is then ready for winding the cone. Power is applied to drive the winding-spindle 3 and rotation is communicated therefrom through the pulleys 6, 8 and belt 7 to the gears 10 and 11 to drive the cam-shaft 4. As the spindle 3 rotates, the yarn is wound onto the tube X, and meanwhile the cam 26 acts to reciprocate the crosshead 30. Motion is communicated from the crosshead 30 to reciprocate the traverse-slide 23, and the traverse-bar 15 is thereby reciprocated to traverse the thread-guide 14 back and forth along the surface of the tube X. As the yarn builds up on the tube X in superimposed layers of helical coils the growing diameter of the package forces the thread-guide 14 away from the axis of the cone-holder 13, thereby causing the traverse-frame 15 to swing back in the direction indicated by the arrow z, Fig. 3. This swinging movement of the traverse-frame 15 causes the traverse-slide 23 to be carried out along the inclined arm or cam-sector 42. As the slide 23 advances outwardly on the cam-sector 42 the traverse-bar 15 will be shifted in an axial direction toward the

apex end of the cone. In this way the traverse-guide 14 carried at the end of the traverse-rod 21 is gradually advanced away from the base end of the package so that 5 each layer of winding will be displaced in the direction of the apex or small end of the cone. As the winding progresses the traverse of the thread-guide is gradually displaced along the cone-holder 13 to cause 10 it to deposit the yarn in stepped-back layers progressively receding from the larger end of the cone and approaching the outer, smaller end. In other words, the cone is built up in progressively-advanced layers 15 so that the mass gradually assumes a convex contour at the base of the cone and a hollow concave formation at its apex end as indicated by the dot-and-dash lines in Fig. 1.

It will be understood that the object of 20 giving this concavo-convex shape to the opposite ends of the cone is to provide a more stable structure of its mass while also facilitating the delivery of the yarn in unwinding it from the package. The convexing of 25 the base of the cone produces a more stable structure, better able to resist rough treatment in handling and packing, while also providing that the package may be set on its base without contact of the yarn with 30 the surface on which the cone is supported. That is to say, when the cone-tube X is set on a horizontal support the ends of the layers at the base end of the cone will incline upwardly away from the support so 35 that the yarn will not contact therewith, and thus the ends of the layers will not be damaged or deranged to prevent free unwinding of the yarn. The advancing or stepping forward of the ends of the layers 40 at the base end of the cone gives a much stancher structure to the whole mass, while the cup-shape form at the small end of the cone also tends to protect the layers and add to the general stability of the whole 45 package. The most important feature of improvement, however, resides in the fact that the coils of winding are prevented from overrunning the end of the cone at its base. That is to say, the coils will be 50 prevented from slipping down over the edge of the cone at the ends of the layers or becoming pulled over in loose lengths extending across its base. Such overruns or 55 "cobwebs," as they are termed, tend to interfere with the delivery of the yarn when it is drawn off over the small end of the cone and frequently causes straining or breaking of the strands before the end can be released.

60 I am aware that it is not broadly new in the art to produce a cone-package having its layers progressively displaced to form a convex base and a concave apex end. Heretofore, however, this method of winding the 65 cone has usually been applied to machines

of the drum- or friction-driven type, and in shaping the ends of the cone it only required the shifting of the cone-holder along the drum during the winding. The present machine is distinguished from winders of the drum type in that the cone or package is rotated positively from the winding-spindle instead of being driven through frictional contact of its surface with a drum or drive-roll. In drum winders the yarn is not laid uniformly and precisely in accordance with a regular system, but the coils are wound open and in a haphazard manner, and the resultant package is inferior to a positively-wound cone. In the present machine the winding-spindle and traverse thread-guide are driven at a constant rate of speed with a uniform synchrony between their operation whereby a regular, systematic and precise disposition of the coils or turns of the winding is arrived at.

The present type of machine is known as a positive or "precision" winder, and heretofore has not been adapted to wind cones of the present type by shifting the traverse of the thread-guide. It has before been proposed to shift the cone itself in relation to the thread-guide, such a form of machine being illustrated in U. S. Patent No. 1,258,824, granted to George N. Taylor Mar. 12, 1918. In this prior type of machine means are provided for sliding the cone longitudinally of the winding-spindle from which it is rotated, and this means is operated by the swinging movement of the traverse-frame. It has been found in practice that such a type of machine is open to certain objections as requiring minutely-accurate coördination of the parts which operate the cone-shifting mechanism. A slight error in the relation or adjustment of these parts will sometimes cause a dislocation of the thread-guide whereby its proper functioning cannot be secured. That is to say, it has been the experience that after the traverse-guide has been moved away from the cone-holder to piece up an end, in returning it to position it is well nigh impossible to set it in the same relation to the winding as before the traverse-frame was displaced. If the guide is not set back in exactly the same place from which it is removed, it will not dispose the layers properly in building the remainder of the cone, and in fact frequently the coils of the winding will be carried too far one way or the other so that the yarn will slip over the edge of the cone and cause overruns or "cobwebs." My present improvement is designed to overcome these objections to this previous type of machine above referred to, being of simpler structure and much easier to manufacture while being proof against dislocation or misadjustment. The direct connection between

the reciprocating crosshead and the traverse-slide acts automatically so that after the thread-guide has been moved away from the surface of the package it can be returned in exactly the same relation without danger of disrupting the synchrony of cooperation between the winding-mandrel and the guide. Furthermore, the displacement of the guide requires less power than to shift the relatively heavy cone-holder itself, especially when the cone on the latter is nearing completion and of considerable bulk. The thread-guide, the traverse-slide and their connections are relatively light in weight, and hence can be displaced very easily without causing the traverse-frame to encounter abnormal resistance as it moves away from the winding-spindle. The shifting of the thread-guide is made consequent to the normal functioning of the general elements of the winding-mechanism, and it will be noted that very few new parts are required to effect the action desired. Furthermore, such additional parts as are employed are of simple construction, economical to manufacture, and the complete device may be employed as a fitment or attachment for standard types of machines already in use. That is to say, it can be applied to the machine without any considerable alteration or reconstruction of its original parts and without requiring material refitting thereof. As before stated, the mechanism is proof against derangement and is adapted for long wear without deterioration.

It is to be observed that the present invention relates to a type of machine which is distinctive from the usual bobbin or pirn winder. That is to say, the present improvement is directed to machines for producing cone-packages of relatively great bulk, and should not be confused with machines for winding filling-cops or bobbins. In bobbin-winders it has been a common practice to shift the traverse of the thread-guide in relation to the winding-spindle during the winding so that the cop grows through longitudinal extension instead of by diametrical increase. This form of package, however, is not composed of layers of uniform length equal in extent to the full length of the cop. Neither is it built up with a relatively flat, but slightly convex base, and a concave small end, but on the contrary both ends are pointed or tapered. As before stated the present invention distinguishes from this latter type of winder in that it operates on a different principle to produce a different form of package which is applied to a different use from that of a bobbin or pirn.

Various modifications might be made in the structure and arrangement of the parts of my improved device without departing

from the spirit or scope of the invention. Therefore, I do not limit myself to the exact embodiment herein shown or described, but neither do I claim broadly a mechanism for shifting the relative position of the cone-holder and the traverse of the thread-guide. 70

What I do claim is:—

1. In a winding machine, the combination with a rotating winding-mandrel, of means to traverse the yarn on the mandrel, means for reciprocating the traversing-means, and means connecting the traversing-means with the reciprocating-means to cause the traverse of the yarn to be continuously advanced in one direction longitudinally of the mandrel whereby to progressively displace the successive layers of winding to build the package with concavo-convex ends. 75

2. In a winding machine, the combination with a rotating winding-mandrel, of means to guide the yarn onto the mandrel, means to effect a traversing motion between the guiding-means and mandrel, reciprocating-means for operating the traversing-means, and means connecting the traversing-means with the reciprocating-means to progressively and continuously advance the layers of winding in one direction longitudinally of the mandrel to build up the package with a concavo-convex formation at its 90 ends. 95

3. In a winding machine, the combination with a rotating winding-mandrel, of means to guide the yarn onto the mandrel, means to cause a relative traversing motion between the guiding-means and mandrel, reciprocating-means for operating the traversing-means, and means connecting the traversing-means with the reciprocating-means to progressively displace the layers 105 of winding in one direction longitudinally of the mandrel, said displacing means being operated by the growth in the winding to cause the package to be built up with concavo-convex ends. 110

4. In a machine for winding frusto-conical packages, the combination with a rotating cone-holder, of a thread-guide for traversing the yarn longitudinally of the holder, means to reciprocate the thread-guide opposite the holder, and means connecting the guide with its reciprocating-means and operating to displace the traverse of the guide in the direction of the apex of the cone to progressively advance the layers of winding to cause the base of the cone to assume a convex formation while its apex end is correspondingly concaved. 115 120

5. In a machine for winding frusto-conical packages, the combination with a rotating cone-holder, of a thread-guide for traversing the yarn throughout the length of the holder, a cam for reciprocating the guide, and automatically-operated means connecting the cam with the guide to cause 125 130

the latter to advance progressively in the direction of its traverse throughout the winding to displace the layers of yarn in stepped relation whereby to build the cone
5 with a convex base and a concave apex end.

6. In a machine for winding frusto-conical packages, the combination with a rotating cone-holder, of a thread-guide for traversing the yarn longitudinally of the holder,
10 a traverse-slide connected to reciprocate the guide, a cam for reciprocating the slide, and automatically-operated means intermediate the cam and slide for shifting the slide progressively in relation to the cam to displace
15 the thread-guide whereby to advance the layers of winding to step them forward to build the cone with a convex base.

7. In a machine for winding frusto-conical packages, the combination with a rotating cone-holder, of a thread-guide for traversing the yarn longitudinally of the holder, a cam, a crosshead reciprocated from the cam, a slide connected to reciprocate the guide, and means connecting the
25 crosshead to reciprocate the slide while causing the latter to be gradually displaced in relation to the crosshead to operate the thread-guide with a progressive advance of its traverse along the cone.

30 8. In a cone-winding machine, the combination with a rotating cone-holder, of a traversing thread-guide adapted to recede from the cone-holder as the winding increases in diameter, means to traverse the
35 guide, and means influenced by the movement of the guide away from the cone-holder to effect a gradual displacement of the traverse of the guide longitudinally of the holder to advance the layers of winding to
40 ward the apex of the cone whereby to build the latter with a convex base.

9. In a cone-winding machine, the combination with a rotating cone-holder, of a thread-guide adapted to be traversed opposite the holder, means to traverse the guide, a traverse-frame for supporting the guide to adapt it to recede from the cone-holder as the winding increases in diameter, and means influenced by the movement of the
45 50 traverse-frame to effect a gradual shifting of the traverse of the guide to progressively displace the layers of winding in the direction of the apex of the cone to build the latter with a convex base.

55 10. In a cone-winding machine, the combination with a rotating cone-holder, of a thread-guide adapted to be traversed opposite the holder, a reciprocating crosshead connected to traverse the guide, and a cam-member arranged to progressively advance the guide in relation to the crosshead whereby to displace the layers of winding toward the apex end of the cone to cause the latter to be built up with a convex base.

60 65 11. In a cone-winding machine, the com-

bination with a rotating cone-holder, of a thread-guide adapted to be traversed opposite the holder, reciprocating-means for traversing the guide, a cam-member arranged between the reciprocating-means
70 and the guide, and means traveling on the cam-member to gradually displace the guide in relation to its reciprocating-means to advance the layers of winding toward the apex end of the cone to build the latter with a
75 convex base.

12. In a cone-winding machine, the combination with a rotating cone-holder, of a thread-guide adapted to be traversed opposite the holder, a crosshead for traversing
80 the guide, means to reciprocate the cross-head, a cam-member carried by the cross-head, and means connected with the guide and slidable on the cam-member to effect a gradual displacement of the guide with respect to its reciprocating-means whereby to advance the layers of winding toward the apex end of the cone to build the latter with
85 a convex base.

13. In a cone-winding machine, the combination with a rotating cone-holder, of a thread-guide adapted to be traversed opposite the holder, a cam for traversing the guide, a crosshead reciprocated from the cam, a slide connected to the guide and
90 adapted to be reciprocated from the cross-head, an inclined cam-member on the cross-head, and means on the slide movable along the cam-member to progressively displace the guide whereby to advance the layers of
95 winding toward the apex end of the cone to build the latter with a convex base.

14. In a cone-winding machine, the combination with a rotating cone-holder, of a thread-guide adapted to be traversed opposite the holder and arranged to recede therefrom with the increase in diameter of the winding, reciprocating-means for traversing the guide, a cam-member connected with the reciprocating-means, and means
100 connected with the guide and movable along the cam-member as the guide recedes from the holder to gradually displace the guide with relation to its reciprocating-means to shift the layers of winding to build the cone
105 with a convex base.

15. In a cone-winding machine, the combination with a rotating cone-holder, of a thread-guide adapted to be traversed opposite the holder, a traverse-cam, a crosshead
110 slidable on a fixed track and connected to the cam to be reciprocated therefrom, a slide connected with the guide and slidable on a movable frame, and an inclined cam-member extending between the crosshead and slide
115 whereby when the latter is moved with its frame it will be displaced laterally with respect to the crosshead during its reciprocation therefrom in the manner and for the purpose substantially as described.

16. In a cone-winding machine, the combination with the main-frame thereof, of a winding-spindle rotatable in bearings thereon, a cone-holder rotated from said 5 spindle, a traverse-frame pivoted on the frame to adapt it to swing away from the cone-holder, a thread-guide adapted to be reciprocated on the traverse-frame, a traverse-cam, a track fixed on the main-frame, 10 a crosshead slidable on said track and connected to be reciprocated from the cam, a

traverse-slide slidable on the traverse-frame and connected with the thread-guide, and an inclined cam-member connecting the crosshead with the traverse-slide and slidable in one of them whereby to displace the thread-guide in the direction of its traverse in the manner and for the purpose substantially as described. 15

In testimony whereof I affix my signature. 20

GEORGE MARCROFT.
